JP D1440190 S 5/2012

Primary Examiner — Patricia A Palasik*(74) Attorney, Agent, or Firm* — Global IP Counselors, LLP(57) **CLAIM**

The ornamental design for a miter saw, as shown and described.

DESCRIPTION

FIG. 1 is a front perspective view of a miter saw in accordance with our new design;

FIG. 2 is a rear perspective view of the miter saw in accordance with our new design;

FIG. 3 is a front elevational view of the miter saw in accordance with our new design;

FIG. 4 is a rear elevational view of the miter saw in accordance with our new design;

FIG. 5 is a top plan view of the miter saw in accordance with our new design;

FIG. 6 is a bottom plan view of the miter saw in accordance with our new design;

FIG. 7 is a right side elevational view of the miter saw in accordance with our new design; and,

FIG. 8 is a left side elevational view of the miter saw in accordance with our new design.

The drawings include gray-scale shading which represents contour, not surface ornamentation or any particular color. The blade guard of the miter saw is transparent.

1 Claim, 8 Drawing Sheets(56)
